UNITED STATES PATENT OFFICE.

PETER WHITE, OF ST. LOUIS, MISSOURI.

WATER-CLOSET VALVE.

SPECIFICATION forming part of Letters Patent No. 247,789, dated October 4, 1881.

Application filed December 27, 1880. (Model.)

To all whom it may concern:

Be it known that I, PETER WHITE, of St. Louis, Missouri, have made a new and useful Improvement in Water-Closet Valves, of which 5 the following is a full, clear, and exact description, reference being had to the annexed drawings, making part of this specification, in which—

Figure 1 is a vertical longitudinal section 10 taken through the improved valve; Fig. 2, a longitudinal section taken at right angles to that of Fig. 1, and looking in the direction indicated by the arrow of Fig. 1. The valve is shown closed. Fig. 3 is a longitudinal section, 15 upon an enlarged scale, of the upper portion of the movable parts of the valve, the view being in the same direction as that of Fig. 1, and the valve being opened; Fig. 4, a longitudinal section of the parts shown in Fig. 3, 20 but at right angles to the view of Fig. 3, and showing the valve closed; Fig. 5, an elevation showing the relief-valve opened and the parts immediately therewith connected, the view being taken in the direction of that of Fig. 2; Fig. 6, a horizontal section taken on the line $x-x$ of Fig. 3; Fig. 7, a top view of the eye of the relief-valve stem; and Fig. 8 an elevation of the parts shown in Fig. 4, but modified by omitting the guide-stem in the lower 25 end of the eye.

30 The same letters denote the same parts.

The present improvement relates, mainly, to the "relief-valve," so called, and the parts immediately therewith connected.

35 Referring to the drawings, A represents the main chamber of the valve, and in which the movable portion of the valve mechanism is held and operated. The inlet to the valve is at B and the outlet at C. The main valve D seats at d, and is attached to the stem d'. The latter, at its upper end, is provided with an extension, E, that is mortised or perforated transversely at e, to receive the eye of the relief-valve stem, and above the perforation e is 40 perforated longitudinally, at e', to receive the relief-valve stem, and provided with the seat e² upon its upper end. F G represent cup-leather valves, the first attached to the stem d' beneath the extension E, and the second to 45 the extension E, beneath the seat e², and conveniently held in place by screwing the exten-

sion E onto the stem d' and the seat e² onto the extension E, as shown.

H represents what is termed the "relief-valve." It seats upon the seat e², as seen in Fig. 5 55 4, being furnished with suitable packing, h, and it is attached to the stem h', which is held and arranged to work up and down in the perforation e', and which, at its lower end, is connected with the eye h², the connection being 60 preferably effected by screwing the stem into the eye, as shown. The eye h² and the perforation e are relatively suitably proportioned and shaped to enable the eye to be moved up and down in the extension E sufficiently to 65 open and close the relief-valve H.

I represents the lever connected with the customary float (not shown) in the water-closet. The lever is pivoted at i, vibrates in the side chamber, a, and is connected indirectly with 70 the main valve D and directly with the relief-valve H, as follows: The arm i' of the lever extends and engages in the eye h² of the relief-valve stem, causing the eye and relief-valve to move immediately with the lever, and ultimately the main valve to move as the eye, above or beneath, as the case may be, encounters the extension E, the operation of the mechanism, more particularly described, being as 75 follows:

80 As the contents of the closet-pot are, and in the usual manner, discharged from the pot, and the float thereby caused to descend, the arm i' of the lever I rises and lifts the valve H from the seat e². The water above the cup-leather G then passes, as indicated in Fig. 3, 85 down through the perforation e' (the stem h' being suitably channeled, as seen in Figs. 3, 6, to provide for the easy passage of the water) into the chamber e within the extension 90 E, and thence out through the chamber a into pot. The groove h³ in the top of the eye h² provides a channel for the escape of the water after the eye h² has encountered the roof of the chamber e. The float continuing to descend after the eye h², in its upward movement, has encountered the extension E, the latter also is raised, and the main valve thereby unseated, permitting the water to pass the main valve, as indicated by the arrows in Fig. 1. 95 The water from the main then flows into the pot, causing the float therein to rise again. 100

The inner arm, i' , of the lever I then descending draws the eye h^2 and relief-valve H downward until the eye h^2 encounters the bottom of the chamber e, whereupon the entire valve mechanism is forced by the float downward in the valve-chamber A, and the main valve D is seated. Thus the movements both of the main valve and of the relief-valve are initiated and insured by the action of the float-lever I operating positively upon these parts. The water from the main passes into the uppermost part of the valve-chamber, above the valve G, by means of the side pipe or passage, K, the inlet to which is at k, beneath the main-valve seat, and the outlet at l'. The office of the valve H is to relieve this pressure from the main from above the valve G when it is desired to lift the valve D. The amount of water flowing through the passage K is regulated by the screw-plug L. The stem of this plug is threaded at l, and is made to screw into a bearing at l', and the outer end of the stem passes through a stuffing-box, l''. By screwing the plug inward the inlet in the passage K is diminished and the pressure transmitted through the passage thereby diminished. Thus from the outside of the valve-chamber the valves can be adjusted to the pressure in the main. In place of the box l'', and having the stem 30 of the plug L pass entirely through to the outside of the valve-chamber, a removable cap can be arranged to be screwed onto the bearing l', over the outer end of the stem, and the joint can be packed by means of packing with- 35 in such cap.

To assist in guiding the movement of the

eye h^2 the latter may be perforated at h^4 to admit a stem, d^2 , that is attached to the stem d' or extension E. When the stem d^2 is not used the construction may be as shown in Fig. 8. 40 The cup F prevents the water from passing upward in the valve-chamber, and the cup G prevents the water above it from passing downward. The valve-chamber has the usual cap, M.

I claim—

45

1. The combination, in a water-closet valve, of the valve D, stem d' , extension E, having the perforation e, the valve H, stem h' , eye h^2 , and lever I, substantially as described.

2. In a water-closet valve, the combination 50 of the main valve D, stem d' , extension E, and the relief-valve H, the latter being seated and working in the upper end or extension of the main-valve stem, substantially as described.

3. The combination of the chamber A, valve 55 D, stem d' , extension E, leathers F G, valve H, stem h' , eye h^2 , and lever I, substantially as described.

4. The combination, in a water-closet valve, of the main valve, relief-valve, and float-lever, 60 said lever being connected directly with and positively moving the relief-valve, and the latter in turn being connected with and positively moving the main valve, the movement of the relief-valve being, in opening and closing, in 65 advance of the movement of the main valve.

Witness my hand.

PETER WHITE.
